UNITED STATES PATENT OFFICE.

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed September 3, 1924. Serial No. 735,556.

In certain classes of work in which the fan-fold type of machine is used, it is necessary from time to time to make out a card containing certain data, which relates to 5 certain printed matter on a work-sheet, which sheet is made out immediately following the card on said fan-fold machine. For instance, a typist may be engaged in typing installation orders on detachable blanks 10 forming a continuous web, for distribution among the various departments of a telephone company. For certain purposes it is necessary to make a card memorandum of the installation order, and it is desirable for 15 certain other reasons that this card be made out immediately before making out the installation order.

In order to save time and labor, it is also 20 desirable that this card be made out by the typist operating the fan-fold machine and on the same machine. This is done by mounting a card-holder between the usual tearing-off knife and the platen, and providing other equipment whereby the card may 25 be inserted into the machine at the front of the platen and rotated backward and forward until the line on which it is desired to print is level with the printing point. Heretofore in inserting such a card in this 30 way, the bottom end of the card was liable to catch on the type-guide, the ribbon and its vibrator, or other obstructions.

One of the features of the present invention is the provision of means to overcome 35 this objection. This is accomplished by inserting the bottom end of the card behind the upper free end of the continuous web and then rotating the platen backward. In this way, the bottom end of the card is protected and the card readily passes the ribbon 40 and its vibrator on its rearward journey. The card is then advanced so that the desired line thereon is level with the printing point on the platen.

It is also desirable, in this class of work, 45 to print on the extreme top and bottom ends of the card, but difficulty has been experienced in holding the card in position on the platen for typing on the extreme bottom end thereof. When said bottom end of the card passes beyond the bite of the front feed-rolls on its forward movement, there is nothing to press the card against the platen with the result that the card becomes crooked on the platen, and the bottom

end thereof bulges out making it impossible to type thereon. Furthermore, owing to the overlapping of the bottom end of the card by the free end of the web in the initial step in inserting said card in the machine, 60 and the further overlapping of said bottom end by the web during the course of the backward rotation of the card, said bottom end of said card is hidden by the lap of the web when it nears the printing point on the machine. This necessitates the removing of 65 the free end of the web from the card, to enable the bottom end thereof to be typed on.

Another feature of the present invention 70 is the provision of means for holding said card firmly against the platen after the bottom end of the card advances beyond the bite of the front feed-rolls, so that its bottom end is pressed against the platen and 75 so that said card may be shifted with respect to said web to free its bottom end from the overlapping web.

Other features and advantages will hereinafter appear. 80

In the accompanying drawings,

Figure 1 is a front view of a platen and associated parts with the present invention applied thereto.

Figure 2 is a vertical sectional view looking to the right of Figure 1. 85

Figure 3 is a view similar to Figure 2 but showing the leading edge of the work-sheet beyond the bite of the rear feed-rolls.

In the fan-fold machine illustrated in the 90 drawings, the work-sheet or continuous web 10, feeds from a source (not shown) and passes through a carbon-carrier (not shown) in interleaved relation with carbon-sheets, the carbon-carrier being mounted to ride on 95 rails 11. From the carbon-carrier, the work-sheet 10 passes downwardly over a rear paper-table 12 around the platen 13 and between said platen 13 and rear and front feed-rollers 14 and 15, respectively, upwardly to the printing point indicated between the guides 16, at which point, said work-sheet 10 receives the impressions of type 16' and ink-ribbon 17 which is threaded 100 through a vibrator.

In the type of machine shown, the platen 13 is mounted so that it can be displaced and swung upwardly and forwardly in order to introduce the work-sheet 10 in the rear of the platen 13. This is done by mounting 110

said platen 13 on a shaft 19, which is journaled in a swing-frame 20. This swing-frame is pivoted on a rod 21, mounted in the frame 22 on the carriage 23. A latch 24, fixed to the shaft 25 pivotally mounted on the frame 22, catches over a lug 26, formed on the side-piece of the swing-frame 20 and holds the platen 13 in normal position. Said latch 24 terminates in a lever-portion 27 on which 5 is mounted a finger-piece 28. By means of this lever 27, the latch 24 is released from the lug 26 and the frame 20 is permitted to swing upwardly and forwardly. When the platen 13 is returned to normal position, the 10 latch 24 automatically engages said lug 26 again through the pressure exerted by a spring (not shown).

For rotating the platen 13 there is provided the usual hand-wheels 29 mounted on shafts 30, and line-space mechanism (not shown) co-operating with a ratchet-wheel 31 fixed on one of said shafts 30. Secured to each of said shafts 30 is a gear 32, which is in constant mesh with a broad pinion 33 25 fixed on the rod 21. This pinion 33 is in mesh with and drives a gear 34 fixed to either end of shaft 19 upon which the platen 13 is mounted. This gear 34 swings bodily with the swing-frame 20 riding over 30 the face of said pinion 33 thereby keeping in continuous mesh with said pinion 33. When one of the detachable blanks forming the continuous web or work-sheet 10 has been 35 printed on, it is advanced until its leading end abuts against an end gage (not shown) carried on the rod 35, which, gages the next blank to proper position, and the completed blank is detached from the web at the desired point by means of the knife 36 mounted 40 in front of said platen 13.

The present invention is concerned with means for holding a card or work-piece 37 in position on the platen 13 of said machine, and especially the lower end of said card, 45 and also with equipment co-operatively combined with the foregoing machine for facilitating the introduction of said card into the machine at the front of the platen. Ordinarily in inserting the card 37 into a 50 machine at the front of the platen, the lower end 38 of said card usually bulges out and catches into the ribbon 17 and its vibrator. To overcome this objection, in accordance with the present invention, the free end 39 55 of the work-sheet or web 10 is advanced slightly and the bottom end of the card 37 is inserted behind said free end 39. This overlapping by the free end 39 protects the ribbon 17 and its vibrator from interference 60 by the lower end 38 of the card 37, and the card may be readily rotated rearwardly for the purpose of bringing the desired line on said card 37 level with the printing point on the platen 13. During this rearward movement, the lower end 38 of the card 37 and

the free end 39 of the work-sheet 10 keep their relative positions until the free end 39 is fed clear of the bite of the rear feed-rollers 14, as will be seen from Figure 3. When said free end 39 reaches this point, its rearward movement is stopped and if the rearward movement of the card 37 is continued before the desired line thereon is brought to the printing point, a greater portion of the lower end 38 of the card 37 is overlapped 70 by the free end 39 than is desired, and upon the forward feed of the card 37, the work-sheet feeds forward also, with the result that the relative positions of the lower edge 38 of the card 37 and the free end 39 of the 75 work-sheet 10, at the time the forward movement is commenced, are maintained when the free end 39 reaches the printing point. As the lower end 38 of the card 37 is considerably overlapped when it reaches the 80 printing point on its advance movement, and as it is desirable to print on said lower end of the card 37, the card 37 must be shifted relative to the work-sheet 10 in order to expose said lower end 38 for printing thereon. Furthermore, as said lower end 38 in its forward movement rides free of the bite of the front feed-rollers 15 before it reaches the printing point (as will be apparent from 85 Figure 2), there is nothing to press said lower end 38 against the platen 13 with the result that the card becomes crooked, its lower end 38 bulging out. It is the concern of the present invention to hold said lower end 38 firmly against the platen 13 after it has 90 ridden free of the bite of the front feed-rollers 15. This is accomplished by mounting a card-holder or guide 40 on a front table 41 at one side thereof. This card-holder 40 is 95 formed of a single strip of flat metal. It 100 comprises a downwardly-extending body-portion 42 and an intermediate slanting portion 43, and a downwardly-extending card-engaging portion 44. It will be noted from Figures 2 and 3, that the card-engaging portion 44 conforms to the curvature of the platen 13 and extending downwardly from a point above the printing point on the platen to a point below the printing point and is 105 of such thickness so as to readily fit between the knife 36 and the platen 13. It will also be noted that the card-engaging portion 44 terminates in an upwardly curved lip 45 for guiding said card during its forward movement. The card-engaging portion 44 is offset from the body-portion 42 in order to 110 permit the card to move relative to the card-holder.

In operation the card 37 is guided beneath and clear of the knife 36 by the holder 40. The card-engaging portion 44 may be lifted by means of the lip 45. The free end 39 of the work-sheet 10 is then advanced and the bottom end 38 of the card 37 is placed between said free end 39 and the platen 13. 115 120 125 130

The platen 13 is then rotated rearwardly until the first line desired to be typed on the card 37 is brought level with the printing point. The free end 39 protects said bottom end 38 during its rearward movement so that said bottom end 38 readily passes the ribbon 17 and its vibrator. During the rearward movement of the platen 13, the free end 39 is fed clear of the bite of rear rollers 14 before the desired line on card 37 is brought to the printing point, with the result that the card 37 feeds rearwardly a short distance after the rearward movement of said work-sheet is stopped. This causes the work-sheet to overlap the bottom end of said card 37 more than is desired, as will be seen from Figure 3, and when upon forward movement of the platen 13, the free end 39 reaches the printing point, the lower end 38, on which it is desired to print, is hidden by the lap of work-sheet 10, necessitating the shifting of said card to expose said lower end 38 for printing thereon. The card-engaging portion 44 extending from a point above the printing point to a point below said printing point firmly presses the bottom end 38 against the platen at the printing point thereon affording a solid base for said bottom end 38 in order to receive satisfactory impressions thereon by the type 17.

It will be seen that the work-web not only provides a supply of detachable typing sections, but also forms in combination with the mechanism of the machine an equipment for front-insertion of cards to be typed prior to filling out the successive sections of the web. The leading edge of each detachable section forms the means for aiding the introduction of its associated and identifying card.

Variations may be resorted to within the scope of the invention, and portions of the improvements may be used without others.

Having thus described my invention, I claim:

1. In a web typewriting machine, the combination with a revoluble platen and a tearing-off knife extending therealong, of a device positioned between the platen and said knife for guiding a card clear of said knife as said card is front-inserted downwardly around the platen.

2. In a web typewriting machine, the combination with a revoluble platen and a tearing-off knife extending therealong, of an introductory work-table adjacent the front of said platen, and a guide carried by said table and including a portion extending between said platen and the tearing-off knife, said guide being effective to direct a card clear of the tearing-off knife during a downward

front insertion of said card around the platen, said guide terminating in a finger co-operating with said platen to hold the card against the platen adjacent the printing line.

3. In a web typewriting machine, the combination with a revoluble platen and a tearing-off knife extending therealong, of an introductory work-table adjacent the front of the platen, and a guide including a finger secured at its upper end to the work-table and extending downward between said knife and the platen in spaced relation to the latter, said finger being effective to deflect a card away from said knife during front introduction of said card downwardly between said knife and the platen, the lower portion of said finger being directed inward to engage the platen adjacent the printing line, whereby to hold the card during typing and to aid said platen in line-spacing the card.

4. In a web typewriting machine, the combination with a revoluble platen and a tearing-off knife extending therealong, of a front-introductory work-table, and a resilient finger attached at its upper end to said table and including a resilient portion extending downwardly in spaced relation to said platen between the latter and the tearing-off knife, the lower free end of said finger being directed inward, so as to engage the platen and terminating in a lip-portion turned away from said platen, the platen-engaging portion of said finger being offset from the point of attachment thereof, whereby said card may feed past the latter during line-spacing.

5. In a web typewriting machine, the combination with a revoluble platen and a tearing-off knife extending therealong, of a front-work-introductory table, a combined guide and card-holder formed of a single strip of resilient material, and means for holding the upper end of said strip to said work-table, said strip being curved downward in spaced relation to the platen and between the latter and the tearing-off knife, the lower end of said strip being in engagement with the platen and having a lip-portion turned outwardly from said platen, said strip being effective to engage the lower edge of a card introduced downwardly upon said table and between the platen and the tearing-off knife, whereby to shield said card from the knife, the lower end of said strip being effective to hold the card against the platen to facilitate typing and line-spacing thereof.

JESSE A. B. SMITH.
